UNITED STATES PATENT OFFICE.

WILLIAM E. DUNCAN, OF SOUTHBURG, CONNECTICUT.

MEAT-CUTTER.

SPECIFICATION forming part of Letters Patent No. 554,663, dated February 18, 1896.

Application filed December 29, 1894. Serial No. 533,235. (No model.)

To all whom it may concern:

Be it known that I, WILLIAM E. DUNCAN, a citizen of the United States, residing at Southington, in the county of Hartford and State of Connecticut, have invented certain new and useful Improvements in Meat-Cutters, of which the following is a specification.

My invention relates to improvements in meat-cutters, and the chief object of my improvement is to so form the delivery end of the case and rotary cutter and forcer that they may be cast in the proper form without coring, whereby they are not only more cheaply produced but can be given a more efficient form.

In the accompanying drawings, Figure 1 is a perspective view of my meat-cutter. Fig. 2 is a central longitudinal section of the case. Fig. 3 is a detached elevation of the delivery end of the case looking squarely into said end. Fig. 4 is a side elevation of the combined rotary forcer and cutter, the two parts thereof being represented as somewhat separated in order to better show that they are separately constructed; and Fig. 5 is an axial section of the delivery end of the combined rotary forcer and cutter.

The body A or main portion of the case may be of the ordinary form, the same being mainly cylindrical with the hopper B near one end, and the bearing 6 for the shaft 7 of the combined forcer and cutter at said end, while the interior is provided with feeding-ribs 8. If these ribs are combined with a closely-fitting rotary forcer they will cut as well as feed; but it is not necessary to my improvement that they shall be thus closely fitted. This portion of the case can be made in the ordinary manner—that is, by casting on a core.

In order that the delivery end C of the case may be cast without coring and at the same time be given an efficient form, I make it separately from the case and provide the confronting faces of the parts A C with flanges 9, in which screws, as at 10, may be secured for holding said parts together. In lieu of the flanges and screws other known means of securing two parts together may be employed—as, for example, providing said parts with concentric male and female screw-threaded por-

tions and screwing them together. This delivery end is made to taper or flare outwardly, the inner diameter at its smallest end corresponding substantially with the inner diameter of the body A of the case: Upon its inside I form cutting-ribs 11, which preferably extend somewhat obliquely to the length of the case and are also made hooked or overhanging on that side toward which the peripheral portion of the combined forcer and cutter moves when in the act of cutting. In order to cast this part without coring it is essential that the inner ribbed surface shall be shaped specially for an endwise draft in molding.

The mouth or larger end of the part C has on its inner side a bearing 12 for the rim 13 of the combined forcer and cutter D E. An inclined face 14 extends from the bearing 12 to the inner edge of the cutting-ribs 11, meeting said ribs at an angle, whereby the ends of said ribs terminate at said face. I have shown every alternate cutting-rib 11 with its edge at the inner end partly cut away, making said cut-away ribs in effect slightly shorter than the others; but this is not material. It is only desirable when one of the ribs terminates midway between two of the feeding-ribs 8, the cutting away avoiding an abrupt shoulder at that point. When a cutting-rib extends directly from in front of a feeding-rib the abrupt shoulder is substantially covered by said feeding-rib.

The forcer or part D of the combined forcer and cutter is or may be of the ordinary form. The delivery end or head E flares outwardly, terminating in the rim 13. Its periphery is provided with cutting-ribs 15, the longer portions of which are fitted to the longitudinal edges of the cutting-ribs 11 of the case, while their shorter edges are fitted to the ends of said ribs of the case where they run out at the inclined face 14. A space is left under the rim 13 between each two adjoining ribs, as best shown in Fig. 1, and each of the cutting-ribs 15 is preferably inclined with reference to the length of said combined forcer and cutter. In order to save stock, I form the delivery end E hollow, as shown, and in order to enable it to be cast by drawing the pattern endwise from the mold without cor-

ing, I form said end E separately from the 5
forcer or part D and subsequently secure
them together by any proper means—as, for
example, with a screw 16 extended through
said end into the end of the part D—while
the dowel-pins 17 in one part, entering proper
sockets or holes in the outer part, insure the
part E from independent rotation.

The part D can be readily cast without cor- 10
ing by drawing the pattern sidewise from the
mold, as with the ordinary forcer. In order
to hold the cutting-ribs of the case and com-
bined forcer and cutter in engagement it is
necessary that said combined forcer and cut- 15
ter be secured against moving endwise. Any
ordinary devices may be employed for this
purpose—as, for example, letting the hub 18
of the crank 19 abut against the end of the
bearing 6 and holding it in place by a collar 20
20 and adjusting-screw 21, the same being a
well-known construction in meat-cutters.

In use the cylindrical portion of the case
and combined forcer and cutter will draw in
the meat and force it along toward the de- 25
livery end, where it will enter the spaces be-
tween the cutting-ribs and be cut, as said ribs
pass one over the other, with a shearing cut.
The meat will be partly cut by the longitudi-
nal portion of the ribs 11 on the case and en- 30
gaging portions of the moving cutting-ribs
15, while the final cut is made by the ends of
the ribs 11 and engaging portions of the ribs
15. The space between the ribs and under
35 the rim 13 leave a free and unobstructed de-
livery of the reduced meat in the lines of the
cutting and forcing blades.

The cutter can be cheaply formed, is of a
compact form, of light weight, and is very
efficient in operation.

40 I claim as my invention—

1. A meat-cutter comprising a case and
combined forcer and cutter, said combined
forcer and cutter having a spirally-ribbed
and substantially cylindrical forcer portion,
45 and a separately-constructed peripherally-
ribbed and outwardly-flaring cutter portion
at the delivery end, with its ribs extending
substantially in the longitudinal direction of
said combined forcer and cutter and at angle
50 to the said cylindrical portion thereof, sub-

stantially as described and for the purpose
specified.

2. A meat-cutter case having at the delivery
end the outwardly-flaring portion provided
with internal and longitudinal cutting-ribs 55
the cutting-edges of which extend along their
length and across their ends, in combination
with a combined forcer and cutter having
continuous cutting-ribs with one portion
fitted to and acting against the longitudi- 60
nally-extended cutting-edges of the ribs of
the case, and another portion of the same
ribs fitted to and acting against the end cut-
ting-edges of the same ribs of the case, sub-
stantially as described and for the purpose 65
specified.

3. A meat-cutter having a combined forcer
and cutter with the outwardly-flaring delivery
end of said combined forcer and cutter pro- 70
vided with the outer rim 13, and substan-
tially longitudinal ribs that extend continu-
ously through the space inclosed by said rim,
substantially as described and for the purpose
specified.

4. A meat-cutter having at the delivery end 75
of its rotary member a conical body portion
or core, and substantially longitudinal ribs
projecting radially from said body portion,
and a rim 13 connecting the outer or top edges
of said ribs at their ends, substantially as de- 80
scribed and for the purpose specified.

5. A meat-cutter having at the delivery end
of its rotary member a series of radially-pro- 85
jecting ribs, and an outer rim the inner di-
ameter of which rim is fully equal to the great-
est cutting diameter as formed by said ribs,
substantially as described and for the pur-
pose specified.

6. A meat-cutter having at the delivery end
of the combined forcer and cutter an outer 90
rim 13, and within said rim the series of radial
ribs which form the sole means of connecting
said rim with said combined forcer and cutter,
substantially as described and for the
purpose specified.

WILLIAM E. DUNCAN.
